[57] **CLAIM**

The ornamental design for the combined staging bracket and double sided clamp back rail, as shown and described.

DESCRIPTION

FIG. 1 is a front perspective view of the combined staging bracket and double sided clamp back rail showing my new design;

FIG. 2 is an enlarged front elevational view of the combined staging bracket and double sided clamp back rail thereof;

FIG. 3 is a rear elevational view of the combined staging bracket and double sided clamp back rail thereof;

FIG. 4 is a right elevational view of the combined staging bracket and double sided clamp back rail thereof;

FIG. 5 is a left side elevational view of the combined staging bracket and double sided clamp back rail thereof;

FIG. 6 is a top plan view of the combined staging bracket and double sided clamp back rail thereof; and,

FIG. 7 is a bottom plan view of the combined staging bracket and double sided clamp back rail thereof.

The broken line showing of partial structure and adjacent bracket is for illustrative purposes only and form no part of the claimed design.
